UNITED STATES PATENT OFFICE.

JOHN H. SCHUSSLER, OF CHICAGO, ILLINOIS.

VIBRATING DISTRIBUTING-ROLLER FOR PLATEN-PRESSES.

No. 875,116.

Specification of Letters Patent.

Patented Dec. 31, 1907.

Application filed March 10, 1906, Serial No. 305,212. Renewed May 8, 1907. Serial No. 372,614.

To all whom it may concern:

Be it known that I, JOHN H. SCHUSSLER, a citizen of the United States, residing at Chicago, county of Cook, State of Illinois, have 5 invented a certain new and useful Improvement in Vibrating Distributing-Rollers for Platen-Presses, and declare the following to be a full, clear, and exact description of the same, such as will enable others skilled in the 10 art to which it pertains to make and use the same, reference being had to the accompanying drawings, which form a part of this specification.

My invention relates in general to printing 15 presses, and more particularly to means for distributing the ink upon the inking rolls of a platen press.

In order that the inking rolls of printing presses may apply ink to the printing surface 20 evenly and uniformly, it is desirable that means should be provided for distributing the ink smoothly over the rolls. By providing such ink distributing means a higher 25 grade of work may be done and greater speed attained owing to the more uniform application of the ink to the printing surface.

The primary object of my invention is to provide a platen printing press with a roll for uniformly and smoothly distributing the 30 ink upon the inking rolls during the entire movement of the inking rolls relatively to the inking disk and printing surface.

A further object of my invention is to provide an ink distributing roll for platen printing 35 presses which will be simple in construction, inexpensive in manufacture, and efficient in use.

My invention as herein disclosed may be generally described as comprising a shaft rigidly supported above and intermediate of a 40 pair of inking rolls of a platen printing press, an ink distributing roll mounted upon the shaft and engaging the surfaces of the pair of inking rolls, and means for moving the distributing roll axially with relation to the inking rolls during their entire movement over the ink supplying disk and over the printing surface.

My invention will be more fully described 50 hereinafter with reference to the accompanying drawing in which the same is illustrated as embodied in two convenient and practical forms, and in which,

Figure 1 is a side elevation of so much of a 55 platen printing press as is necessary to show the connection of my invention therewith;

Fig. 2 a plan view of my invention applied to a pair of inking rolls detached from the press; and Fig. 3 an enlarged central sectional view showing one embodiment of my invention. 60

Similar reference characters are used to designate similar parts in the several figures of the drawing.

Reference character A indicates one side of the frame of a platen printing press. A' 65 indicates the printing surface and A² the ink-supplying surface such as disk.

B designates the inking roll carriage at one side of the press which supports the inking rolls. The carriage B is pivoted at b in the 70 usual manner.

C & C' indicate spring-supported rods carried by the frame B at each side of the press. The rods C support at their upper ends plates c' in which are journaled the ends of a 75 pair of inking rolls D' D². The upper ends of the rods C support the brackets in which are journaled the ends of an auxiliary inking roll D.

The construction above described is well 80 known and forms in itself no part of my invention, but is merely shown for convenience in order that the construction and operation of my improvement may be fully disclosed. It is obvious that my invention may be applied to other forms of platen printing presses 85 than the one illustrated.

Referring more particularly to Figs. 2 and 3, reference character F indicates a shaft supported above and intermediate of the 90 pair of inking rolls D' D². The ends of the shaft F are surrounded by boxes F², F², the latter being mounted in bearings F' F' rigidly secured to the brackets c' c'. A clamp screw f' extends through the top wall of each 95 of the bearings F' into contact with the enclosed block F². The ends of the shaft F are nonrotatably secured within the respective blocks F² by means of cotter pins f², f² which extend through registering holes in the shaft. 100 E indicates a hollow ink-distributing roll mounted upon the shaft F. Secured within one end of the roll E is a ring E' having an interior screw thread engaging the screw thread on a sleeve G. The sleeve G loosely 105 surrounds the shaft F and engages at one end a collar g fixed to the shaft. The end of the sleeve G within the roll E is provided with a disk G' which serves as one member of a clutch. G² indicates a disk which serves as 110 the other member of the clutch and which is provided with a hub having slots therein

through which extends a pin g^3 carried by the shaft F. A spring H surrounds the shaft F and is interposed between the hub of the disk G^2 and a collar h fixed to the shaft F. 5 A rod e' extends through the ring E' and projects at each side thereof as clearly shown in Fig. 3. A radial pin g' is carried by the sleeve G' adjacent the outer end thereof while a second radial pin g^2 is carried by the sleeve G at the inner end of the screw thread thereon.

The operation of the embodiment of my invention above described is as follows: When the inking rolls are in the position 15 shown in Fig. 1, the carriage B is oscillated in the usual manner so that the rolls will pass over the inking disk A^2 and thence over the printing surface A'. The carriage B is then oscillated in a reverse direction which causes 20 the inking rolls to travel upwardly over the printing surface thence over the inking disk to the position shown in Fig. 1. During such travel of the inking rolls they are rotated and through their engagement with the 25 surface of the distributing roll the latter is rotated about the shaft F. As the shaft F is fixed the roll E rotates relatively thereto and owing to the engagement between the screw-threaded sleeve G clutched on the 30 shaft and the interiorly screw-threaded ring E' fixed within the roll, the latter is moved axially with respect to the shaft coincidently with its rotation about the same. When the inking rolls are at the opposite end of their 35 travel from the position shown in Fig. 1, the distributing roll is in the position relative to the shaft F shown in Fig. 3, that is, the pin e' engages at its outer end with the radial pin g' . As the inking rolls travel upwardly the 40 distributing roll will be rotated relatively to the shaft in a reverse direction and hence will be moved axially towards the right in Fig. 3 until the inner end of the pin e' engages the radial pin g^2 . Should the pin e' 45 engage pin g^3 before the inking rolls reach the upper end of their travel and the distributing roll consequently be further rotated with respect to the shaft F, the sleeve G will move with the rolls and relatively to 50 the shaft, such movement being permitted by a slipping between the clutch members G' & G^2 . When the inking rolls are in the position shown in Fig. 1 the inner end of the pin e' is in contact with the pin g^2 and during 55 the downward movement of the inking rolls the distributing roll will move towards the left until the outer end of the pin e' engages the radial pin g' when any further movement of the roll upon the shaft will move 60 with it the sleeve G such movement being permitted by the clutch member G' slipping with respect to clutch member G^2 . In this embodiment of my invention it will be observed that the two members of the clutch 65 may be held in contact with any desired

pressure owing to the tension of the spring H being adjustable by reason of the position of the collar h being variable with respect to the shaft.

The clamp screws f' serve to regulate the 70 pressure with which the distributing roll engages the surfaces of the inking rolls. Changes in temperature as well as usage necessitate an adjustment of the screws f' in order that the contact between the distributing roll 75 and inking rolls will be such as to evenly distribute the ink.

It will be noticed that the inner ends of the boxes F^2 are provided with flanges f^3 which over-lie the adjacent edges of the brackets 80 F'. By making the boxes axially movable upon the shaft it is possible to employ closed brackets inasmuch as the boxes may be moved along the shaft to positions within the brackets and there retained by reason of 85 the flanges on the boxes engaging the inner sides of the brackets and the cotter pins on the outer sides of the brackets. The cotter pins serve not only to retain the boxes within the brackets, but also to rigidly connect 90 the ends of the shaft to the boxes.

From the foregoing description it will be observed that I have invented an improved form of distributing roll for platen printing presses in which the ink will be smoothly distributed upon the inking rolls owing to the continuous axial movement of the distributing roll relatively to the inking rolls during the entire travel of the latter relatively to the inking disk and printing surface. 95

Having now fully described my invention what I claim as new and desire to secure by Letters Patent is:

1. The combination with a platen printing press having an inking surface and a printing surface, of an inking roll, means for moving said roll relatively to the inking and printing surfaces, an ink distributing roll engaging the surface of the inking roll, an axially immovable shaft upon which said distributing roll 105 is rotatably mounted, an integral closed bracket within which an end of said shaft is secured, a box surrounding said shaft within said bracket, and means supported by said bracket for adjusting the position of said 110 box therein to regulate the pressure of the distributing roll upon the inking roll.

2. The combination with a platen printing press having an inking surface and a printing surface, of a pair of inking rolls, means for 120 moving the inking rolls relatively to the inking surface and printing surface, an ink distributing roll mounted intermediate of and in contact with the surfaces of the inking rolls, a fixed shaft upon which the distributing roll is rotatably mounted, a pair of co-operating members interposed between said shaft and distributing roll for axially moving the roll relatively to the shaft, means for locking one member of said pair to the shaft 125 130

5 during a predetermined axial movement of the distributing roll, and means for locking said member to rotate with said roll relatively to said shaft after said predetermined axial movement of the distributing roll.

3. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which the distributing roll is rotatably mounted, a member mounted upon said shaft, a second member carried by the distributing roll and engaging said first member to axially move said roll relatively to said shaft, means for locking said first member to the shaft during a predetermined axial movement of said distributing roll, and means for locking said first member to rotate with the distributing roll relatively to said shaft after said predetermined movement of the distributing roll.

25 4. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which said distributing roll is rotatably mounted, a pair of coöperating members interposed between said shaft and distributing 30 roll for axially moving the roll relatively to the shaft, means for locking one of said coöperating members to the shaft during a predetermined axial movement of the distributing roll, and means for locking said member 35 40 to rotate with the distributing roll relatively to the shaft after said predetermined axial movement of the distributing roll.

5. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which said distributing roll is rotatably mounted, an interiorly screw-threaded ring fixed within said distributing roll, a screw-threaded sleeve around said shaft engaged by said ring for axially moving said distributing roll upon said shaft, means for locking said sleeve to the shaft to effect a predetermined axial movement of the distributing roll, and means for locking said sleeve to rotate with the distributing roll relatively to said shaft after said predetermined movement of the distributing roll.

6. The combination with a platen printing press having an inking surface and a printing surface, of an inking roll, means for moving said roll relatively to the inking surface and

printing surface, an ink distributing roll mounted adjacent and in contact with the surface of the inking roll, a fixed shaft upon which said distributing roll is rotatably mounted, an exteriorly screw-threaded sleeve surrounding said shaft, an interiorly screw-threaded ring fixed within said distributing roll and engaging said sleeve, means for locking said sleeve to said shaft during a predetermined axial movement of said roller, and means for locking said sleeve to rotate with the distributing roll relatively to said shaft after said predetermined axial movement of the distributing roll.

7. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which said distributing roll is rotatably mounted, an exteriorly screw-threaded sleeve surrounding said shaft and an interiorly screw-threaded ring fixed within said distributing roll and engaging said sleeve, and means for frictionally locking said sleeve to said shaft. 80 85 90

8. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which said distributing roll is rotatably mounted, an exteriorly screw-threaded sleeve surrounding said shaft, an interiorly screw-threaded ring fixed within said distributing roll and engaging said sleeve, means for frictionally locking said sleeve to said shaft, and means for rotating said sleeve with the distributing roll after a predetermined axial movement of the roll in either direction. 95 100 105

9. The combination with a platen printing press having an inking surface and a printing surface, of an inking roll, means for moving said roll relatively to the inking surface and printing surface, an ink distributing roll mounted adjacent and in contact with the surface of the inking roll, a fixed shaft upon which said distributing roll is rotatably mounted, an exteriorly screw-threaded sleeve surrounding said shaft, an interiorly screw-threaded ring fixed within said distributing roll and engaging said sleeve, means for frictionally locking said sleeve to said shaft, a radially projecting pin carried by said sleeve at each end of the screw thread thereon, and pins carried by said ring adapted to engage the pins on said sleeve after a predetermined axial movement of the distributing roll in either direction. 110 115 120 125

10. The combination with a platen printing press having an inking surface and a 130

printing surface, of an inking roll, means for moving said roll relatively to the inking surface and printing surface, an ink distributing roll mounted adjacent and in contact with the surface of the inking roll, a shaft upon which said distributing roll is mounted, closed brackets through which the ends of said shaft extend, boxes surrounding the ends of said shaft and axially movable thereon, and means for locking said boxes to the shaft and coincidentally retaining the boxes within said brackets.

11. The combination with a platen printing press having an inking surface and a printing surface, of an inking roll, means for moving said roll relatively to the inking surface and printing surface, an ink-distributing roll engaging the surface of the inking roll, a shaft upon which said distributing roll is rotatably mounted, a closed bracket through which one end of said shaft extends, a box surrounding said shaft and axially movable thereon, means for retaining said box within said bracket, and means for adjusting the

position of said box within said bracket thereby regulating the pressure of the distributing roll upon the inking roll.

12. The combination with a platen printing press having an inking surface and a printing surface, of an inking roll, means for moving said roll relatively to the inking surface and printing surface, an ink-distributing roll engaging the surface of the inking roll, a shaft upon which said distributing roll is rotatably mounted, a closed bracket through which one end of said shaft extends, a box surrounding said shaft and axially movable thereon, a flange around the inner end of said box adapted to over-lie the inner surface of said bracket, and a pin extending through said box and shaft and over-lying the outer surface of said bracket.

In testimony whereof, I sign this specification in the presence of two witnesses.

JOHN H. SCHUSSLER.
